CARPET SWEEPER WHEEL LINKAGE

Paul Heftler, Windsor, Ontario, Canada

Application April 23, 1946, Serial No. 664,390

8 Claims. (Cl. 15—41)

1

The devices described here and shown in the accompanying drawings are carpet sweepers which automatically adjust themselves to the thickness or softness of the rug on which they may happen to be used. They sweep any floor or floor covering, from bare wood or linoleum to the softest and thickest of chenille rugs, without it being necessary to bear down at all on the handle. In fact, they will sweep these surfaces and go from one to the other, adjusting themselves as they go, with their handles removed and being pulled along by a string.

Besides being self-adjusting, these sweepers are very responsive to pressure applied to them by their handles. Thus, when the person using one of these sweepers wants the sweeper to sweep with more power, so as to pick up some stubborn dirt, the sweeper needs less pressure on its handle than any earlier design of carpet sweeper.

Two of the best forms of these sweepers are shown in the drawing. Figure 1 is an end view of the first form, with one wheel and parts of the end iron broken away, and Figures 2, 3 and 4 are sections taken on the lines 2—2, 3—3 and 4—4 in Figure 1. Figure 5 is a graph that is referred to later in explaining the operation of the sweeper. Figure 6 is an end view of the second form or model, and Figure 7 is a view like Figure 6 but with the handle bail, bumper cord and most of the end cover removed to show the mechanism within. Figures 8, 9 and 10 are sections on a slightly larger scale taken on the lines 8—8, 9—9 and 10—10 in Figure 6.

The first form of the new sweeper, shown in Figures 1 to 4, is made with a conventional case 1 having a simple end bar 2 extending across each end to carry a bush pivot 3 and support a bumper 4. The brush pivot also acts as a rivet to hold a bumper clip 5 on the end bar. These parts, as well as the brush 6, brush pulley 7, axles 8, axle tubes 9, dust pans 10 and the mechanism for dumping the dust pans are similar to or are the same as those of sweepers now on the market.

The wheels 11 are of the common ball-bearing type shown in the Mason and Shanahan Patent No. 877,852, but they are mounted inside out as compared with the usual arrangement so that the ball bearing is on the inner side towards the case. Each wheel 11 has a rubber tire 12 cemented to its rim, and it is riveted to the outer end of a hub 13. The fastening of the wheel to its hub is made more rigid by a thick washer 14 placed on the hub against the wheel before the end of the hub is riveted down. The

2

hub 13 is drilled part way through from its inner end to take the end of the axle 8, and the outside of the hub is made with a groove which acts as a raceway for the balls 15. The other raceway is formed by a pair of stampings 16 that are held together by a flange on one of them being clenched over a flange on the other. The stampings 16 have radial arms 16a that lie together and act as a link by which the wheel is connected to the rest of the mechanism of the sweeper.

The axles 8 serve chiefly to hold the wheels in line and to limit their movement to what is permitted by the clearance around the axles 15 in the axle tubes 9. The axles also serve to hold the wheels against moving in against the sides of the case, but to make sure that the ends of the hubs do not catch in the ends of the axle tubes, thin metal washers 17 are provided on the axles between the wheels and the case. The wheels are prevented from moving too far out away from the case by the end bar 2, against which the outer ends of the hubs 13 will come as soon as the wheels move out a fraction of an inch from their proper positions.

The wheel bearing arms or links 16a are connected to the case through a yoke 18 mounted on the end of the case so that it can slide up and down with the wheels. The yoke 18 is a metal plate, and the connections between it and the bearing arm 16a are formed by lugs or fingers 18a bent up from the edge of the yoke and extending straight out through holes in the ends of the links 16a. The ends of the lugs that go through the links curve down and in away from the centers of the wheels so as to prevent any accidental sliding of the links off the lugs. The lugs are placed on the yoke 18 so that the links 16a slope down and in towards each other at angles to the vertical, these angles being about forty-five degrees so that any forces transmitted to the wheels through the links 16a will make the wheels press against the brush pulley 7 just as hard as it makes them press down on the floor or rug 19.

The bottom of the yoke 18 is guided in its up-and-down movements by a pair of round-headed screws 20 that pass through slots 21 in the yoke and into the end of the case, and the top of the yoke is guided by a lever 22 pivoted at one end to the case and at the other end to the yoke. The pivot 23 between the lever and the yoke is a shoulder rivet, and the pivot or fulcrum at the other end of the lever is a stepped collar 24 fixed to the case by a screw 25, the head of

the screw being big enough to keep the lever from sliding off the collar or sleeve 24.

Each of the two yokes 18, one at each end of the sweeper, is provided with two springs 26 which tend to lift the case and push down the yoke. These springs are of the "hairpin" type and are made with several coils connecting the two arms, which extend out at a considerable angle to each other and have loops at their ends. One end loop of each spring is pivoted to the case by a screw 27 driven into the case, and the other end loop is pivoted on an eye or hook 18b on the bottom of the yoke, the two pivots allowing the spring to work with very little friction.

The lever 22 that connects the top of the yoke 18 to the case also connects the handle of the sweeper to the case and to the wheels. The handle is made with the usual handle bail 28, that has, at each end, a pivot 29 riveted to it and projecting in towards the case. The pivot 29 fits into a hole in the lever 22 which forms a bearing for it, so that the only connection between the handle and the case is through the levers 22 (one at each end of the sweeper). The pivot 29 extends also through a slot 30 in the yoke and into a hole 31 in the end of the case, but these are large enough so that the pivot never touches either the yoke or the case and acts only on the lever. The extra length of the pivot is merely to keep it from accidentally coming out of its pivot hole in the lever.

To hold the sweeper handle up when the sweeper is not in use, the upper edge of the yoke is formed into a flange 18c having a notch 18d between two parts that project out into the path of the handle bail 28. As the bail is swung up straight, its legs spring over the projections 18c and then snap into the notches 18d at each end of the sweeper and hold the handle up.

Down to this point, this description of the sweeper has included only those things that might be seen from the drawing. But the most important things about this sweeper are not so easy to see; they are described below.

The first of these things is the strength of the springs 26. They are very flexible, several times as flexible as the springs ordinarily used on carpet sweepers, and they are not strong enough to lift the brush, weighted down by the case, off the floor. In more technical terms, the "rate" of the springs is very low, and the force exerted by the springs is less than the "sprung weight" of the sweeper.

The flexibility or low "rate" of the springs is secured partly by making them of fine wire and providing a considerable length of wire in the coiled parts of the springs and partly by the shape of the springs. Most of the springiness of each spring is in the coils because the forces that act on the springs have more leverage on the wire in the coils than on the wire in the arms. The leverage under which the coils work is equal to the distance from the coils to a line drawn between the ends of the arms. This distance increases as the arms of the spring come together, and the increase in this distance and the leverage off-sets most or all of the increase in the forces exerted by the wire in the coils of the spring as the spring is bent. In fact, if the springs are made so as to be as shown in the drawing when they are in use and to have their arms extending straight out in opposite directions when they are free, the effective rate of the springs will be practically zero.

What the force exerted by the springs should be depends on the weights of the various parts of the sweeper, the torque needed to turn the brush when it is pressing on the carpet, the diameter of the brush, and the diameter of the brush pulley. In this particular sweeper, whose total weight is six pounds, the weight is distributed as follows:

	Pounds
10 Case and parts moving up and down with it, such as brush, end bars, bumper, dust pans, and half of springs and levers	3.5
15 Wheels and parts moving up and down with them, such as axles, bearings, yokes, and half of springs and levers	1.1
20 Lower end of handle and bail resting on the handle pivots	0.9
25 Upper end of handle and bail resting in the hand of the person using the sweeper	0.5
30 Total	6.0

The 0.5 lb. of the handle and bail that rests in the hand has not effect on the working of the sweeper. The 0.9 lb. of the handle and bail that rests on the levers 22 is applied by them to the case and to the yokes, one-third of this weight or 0.3 lb. to the case and two-thirds or 0.6 lb. to the yokes and through them to the wheels. The total weight moving up and down with the case is therefore 3.5 lbs. plus 0.3 lb. or 3.8 lbs. This is called the "sprung weight" because it rests on the springs. The total weight carried directly by the wheels and not through the springs is 1.1 lbs. plus 0.6 lb. or 1.7 lbs. This is called the "unsprung weight" because none of it is carried by the springs.

The diameter of the spring wire and the size and number of coils in each spring is such that the four springs acting together exert a lifting force of 2.9 lbs. on the case. This is 0.9 lb. less than the sprung weight. In other words, the springs are too weak by 0.9 lb. to hold up the case and the parts that move up and down with it. The result is that, whenever the sweeper is set on a floor or rug and rolled along and no matter whether the floor is bare or the rug is thick and soft, the case will sink down until the brush rests on the floor or rug with a pressure of 0.9 lb. The rest of the weight of the sweeper on the floor or rug will be carried by the wheels and will make them press on the floor or rug with the pressure of 4.6 lbs.

When the brush is bearing down on the floor or rug with a pressure of 0.9 lb. it is bearing down hard enough for ordinary sweeping. When the wheels are bearing down with a pressure of 4.6 lbs., they will have enough traction to drive the brush when it is bearing down with a pressure of 0.9 lb. without there being much slippage. This slippage is practically nothing on a hard floor and is about 7% with these pressures on an average rug with a good well-bristled brush. Also, when the wheels are bearing down with a pressure of 4.6 lbs., they are bearing against the brush pulley with a pressure that is practically the same as their pressure on the floor, because of the angles of the links 16a. With this pressure, there is no appreciable slippage between the wheels and the brush pulleys. Thus, not only does the brush automatically rest with the right pressure on the floor or rug but the wheels will have all the traction that they need to drive the brush. Therefore, no matter whether the sweeper is

on a hard floor or a thick soft rug, all that it needs to make it sweep is to be pushed or pulled along, and there is no need to press down on it.

When one wants to make the sweeper sweep with more power, the natural thing to do is to press down on it as it is being moved back and forth. The pressure applied to it is applied through the handle, and this pressure is divided between the yokes 18 and the case 1 by the levers 22. This division is in the ratio of two to one so that, if the added pressure is 3.3 lbs., the added pressure on the yokes will be 2.2 lbs. and the added pressure on the case will be 1.1 lbs. These pressures will be passed on to the wheels and the brush, so that the wheels will bear down with a total pressure of 6.8 lbs., and the brush will bear down with a total pressure of 2.0 lbs. As before, these pressures on the floor or rug are correctly balanced; the pressure of the wheels is enough, but not much more than enough, to get the traction that is needed to drive the brush.

The dead weight of the sweeper is divided between the wheels and the brush in the ratio of about five to one, and the pressure coming through the handle is divided in the ratio of two to one. These ratios are different because the brush does not have the same coefficient of friction when it is pressing down hard as when it is pressing down lightly. If it had, the torque needed to drive it would be proportional to its pressure on the rug. Instead of this, doubling the pressure of the brush on the rug increases the torque needed to drive it by much less than double. The exact relations between the pressure and the torque are shown by the curve in Figure 5, which shows how the torque increases at a slower and slower rate as the pressure is increased.

The ratios in which the weight and the pressures are divided have been chosen to get the most powerful sweeping action possible with the particular brush and other parts used in the sweeper described above. In another sweeper, with fewer bristles in the brush or with a heavier case, these ratios would be different to get the best results. Or different ratios might be chosen if one wanted a sweeper that ordinarily swept very lightly and was very easy to push. For example, the weight of the sweeper might be divided between the wheels and the brush in the ratio of ten to one, but such a sweeper would not be taking full advantage of the invention.

Although the sweeper described above and shown in Figures 1 to 4 is perhaps the best sweeper that has been made, it does have one slight fault; it is not well balanced about its handle pivots. This results in the front of the sweeper lifting up a little when the sweeper is pushed back and forth very quickly. Also, that sweeper, with its open ends, is not stylish. To cure these faults or defects, the improved model shown in Figures 6 to 10 has been designed.

The improved sweeper is made with a conventional wooden case 41, to each end of which is fastened a rounded metal end cover 42, and it is encircled by a rubber bumper band 43 held on in any conventional way. Most of the operating mechanism of the sweeper lies within the end covers, but a handle pivot 44 projects out through a hole 45 in the side of each cover and has one end of the handle bail 46 pivoted on it. The handle bail 46 is in the shape of an inverted U straddling the sweeper with each of its legs lying close against but not rubbing the side of

the end cover. Directly above the handle pivot, two bosses 47 are formed in the end cover so that, when the handle is swung upright, the bail will ride over one boss and snap between the two and thus hold itself upright when the sweeper is not in use.

The brush 48, together with its pulleys 49, is mounted on a pivot 50 riveted to a springy brush pivot bracket 51. The bracket 51 is pivoted at 10 one end on a shoulder rivet 52 fixed to the end cover at one side of and a little below the axis of the brush. The other end of the bracket 51 fits under a hook 53 at its upper edge and above a shoulder 54 at its lower edge, both the hook 15 53 and the shoulder 54 being stamped from the end cover 42, as shown in Fig. 3. Except when the brush is to be removed, the hook 53 and the shoulder 54 hold the bracket 51 from moving either up or down, and thus the brush pivot is 20 ordinarily fixed.

The central part of the bracket 51 is offset away from the end cover and extends down as far as the bottom edge of the end cover, which is cut away a little to make the bracket more 25 accessible. To remove the brush, the lower end of the bracket 51 is pressed in far enough to spring the bracket off the shoulder 54, and the end of the brush held by the bracket is pulled 30 out of the case, the bracket swinging out with the brush. The same operation is performed at the other end of the brush with the other bracket, and then the two brackets are sprung apart far enough to withdraw first one pivot 50 from the 35 brush and then the other. This is easy to do because the two brackets at the opposite ends of the sweeper swing away from each other towards opposite sides of the sweeper, the mechanisms on the two ends of the sweeper being the same and not right and left handed.

40 The handle pivot 44 is not mounted on any fixed part of the sweeper but is carried by a primary lever 55 carried by a pivot 56 fixed to the end cover at the same height as the handle pivot. The other end of the lever 55 is connected by a pivot 57 to a yoke 58, which arches over and down at each side of the brush pulley 49. To make both ends of the yoke 58 move up and down together as the lever 55 moves up and down, a secondary lever 59 is mounted on a fulcrum 60 on the end plate and is connected by pivots 61 and 62 to the primary lever 55 and the yoke. Both of the levers 55 and 59 have a ratio of two to three, the distances being measured horizontally, and the pivot 61 connecting them together has its axis directly above the axis of the handle pivot 44, so the ends of the levers pivoted to the yoke move up and down the same distance at all times, and the yoke moves 45 up and down without tipping.

60 To ensure smooth operation of the levers and the yoke, the fulcrum 60 and yoke pivot 57 of the primary lever are in one horizontal plane, the fulcrum 60 and yoke pivot 62 of the secondary lever are in another horizontal plane, and the two fulcrums 60 and 62 and the interconnecting pivot 61 are in a third plane. Also, the fulcrum end of the secondary lever has a slot to receive the fulcrum 60, which is fixed to the end cover, and the yoke has a slot to receive the pivot 62, which is fixed to the secondary lever. The places where the levers are pivoted to each other or to the yoke are embossed slightly to prevent the parts from rubbing on each other and creating friction at other places, and the yoke end of the 65 primary lever and the fulcrum end of the 70 secondary lever are rounded to prevent friction.

secondary lever are offset so as to lie against the parts to which they are pivoted.

The primary lever 55 is F-shaped, so that its body will not interfere with the brush pivot bracket 51 or the hook 53 into which the bracket fits, both ends of the bracket and the hook lying in approximately the same plane as the lever. The central arm of the primary lever, which carries the handle pivot 44, extends down between the offset central part of the bracket 51 and the end cover 42, as shown in Figure 9, and it is long enough to cover up the back of the hole 45 in the end cover through which the pivot projects. It is also formed with a boss, on which the handle pivot 44 is mounted, high enough to project through the hole 45 in the end cover and to prevent the handle bail 6 from rubbing on the end cover.

The lower ends of the yoke 58 are connected to the wheels 63 through the banjo bearings 64, each end of the yoke having a finger 58a bent in from the body of the yoke and extending through a hole in the end of the banjo bearing arm. The banjo bearings 64, the wheels 63, and the axles 65 are of the well-known type shown in U. S. Patent No. 877,852, and the axles 65 extend through axle tubes 66 in the usual manner. Metal and fibre washers 67 and 68 on the axles space the wheels out from the ends of the case 41 and prevent dust from entering the axle tubes. The dust pan 69 may be of any common type.

The major part of the weight of the sweeper is transmitted to the wheels 63 by the springs 71, one end of each spring engaging a hook 72 stamped out of the end cover 42 and the other end engaging a hook 58b formed on the lower end of the yoke 58. These springs 71 work exactly like the springs 26 in the sweeper shown in Figures 1 to 4, except that the sweeper of Figs. 6 to 10 will be a little heavier and its springs will therefore be a little stronger. If the second sweeper weighs 0.60 lb. more than the first, the springs 71 should each exert a force 0.10 lb. more than the springs 26, so that two thirds of the additional weight is carried by the wheels and one third by the brush.

The sweeper of Figures 6 to 10 operates in the same way, except for the slight difference in weight, as the sweeper of Figures 1 to 4, so there is no need of explaining at length how it works.

The application for this patent is a continuation-in-part of a forfeited application Ser. No. 394,130 filed on May 19, 1941. Although only two specific forms of the invention are described above, the invention covered by this patent is not limited to them but includes any sweeper that fits any of the following definitions or claims.

I claim:

1. In a carpet sweeper, a case, a brush mounted to turn on a fixed axis in the case and having friction pulleys on its ends outside of the case, four wheels movable up and down with respect to the case, one wheel being located on each side of each pulley and arranged to roll on the floor and against the pulley to drive the brush, end covers outside of the pulleys and the wheels, levers lying outside of the pulleys and the wheels and inside of the end covers, each lever being connected at one end to an end cover and at the other end to a wheel, and a handle connected to each lever between its ends.

2. In a carpet sweeper having a rotary brush, a friction pulley fixed to one end of the brush, wheels on both sides of the pulley and arranged

to roll on the floor and against the pulley to drive the brush, and a frame member extending around outside the pulley and the wheels, a handle pivot carrier extending down between the pulley and the frame member and movable up and down, a handle pivot on the handle pivot carrier beside the pulley, mechanism connected to the handle pivot carrier and operated by it for adjusting the sweeper, a horizontally extending brush pivot bracket having one end pivoted to the frame member and having a part normally lying between the handle pivot carrier and the end of the brush and carrying a pivot for the brush, the bracket being long enough so that it can be swung down to carry the brush pivot below the frame member and sprung enough so that the brush pivot can then be sprung out of engagement with the brush, and releasable means for holding the bracket in its normal position on the inner side of the frame member.

3. In a carpet sweeper having a case assembly, a rotary brush in the case assembly, friction pulleys on the ends of the brush, pivots for the brush fixed to the case assembly, and four wheels movable up and down with respect to the case assembly and arranged to roll on the floor and against the pulleys to drive the brush, a pair of handle pivots that can move up and down relative to the case assembly, a primary lever at each end of the sweeper connected to the case assembly at one point and to a wheel at another point and to one of the handle pivots at a point between the first two points, and a secondary lever at each end of the sweeper connected to the case assembly at one point and to a wheel at another point and to the primary lever at a point which is between the first two points on the primary lever and between the first two points on the secondary lever.

4. In a carpet sweeper, wheels for rolling on the floor, a case, a brush projecting below the case so as to rest on the floor, the case and the brush being movable up and down with respect to the wheels, springs connected to the wheels and the case for transferring a portion of the weight of the case and the brush to the wheels, the springs having only enough strength to carry a part of the weight of the case and the brush, the rest of the weight of the case and the brush being carried by the brush throughout the normal range of movement of the wheels relative to the case, a handle connected to the sweeper for moving it on the floor and for applying downward pressure to it, and levers on the sweeper for dividing the pressure applied by the handle between the wheels and the brush in a fixed ratio.

5. In a carpet sweeper, wheels, a brush and other members forming a weight movable up and down with respect to the wheels, springs acting between these members and the wheels and strong enough to carry only a part of their weight so that the brush will sink down and bear on the surface of any floor or carpet on which the sweeper may be placed without any downward pressure being applied to the sweeper, a handle through which downward pressure may be applied, and a lever mechanism for receiving downward pressure from the handle and dividing it between the wheels and the brush.

6. In a carpet sweeper, a brush, wheels movable up and down with respect to the brush, dust pans and other members connected to the brush and forming a weight acting to push the brush down, springs constructed and arranged to trans-

mit a part but not strong enough to transmit all of this weight and the weight of the brush to the wheels, a handle through which downward pressure can be applied, and levers for dividing the downward pressure from the handle between the wheels and the brush.

7. In a carpet sweeper, a case assembly, a brush journaled to rotate on a fixed axis in the case assembly, dust pans carried in the case assembly on both sides of the brush, wheels on both sides of the brush axis, the wheels being movable up and down with respect to the case assembly and arranged to roll on the floor and drive the brush, levers extending from fulcrums on the case assembly to floating connections to all the wheels, and a handle connected to the levers at points between their fulcrums and their floating wheel connections.

8. A floor and carpet sweeper having a case, a handle, a pair of floor wheels at each end of said case, a longitudinally extending rotary brush in said case, a friction pulley on each end of said brush and engaging said floor wheels for driving said brush as said sweeper is pushed across a floor or carpet, means for supporting said brush and said friction pulleys for free vertical movement through a definite range of movement relative to said wheels, means for dividing the weight of said sweeper between said wheels and said brush resting on a floor or carpet in one ratio throughout said range of movement whereby both said wheels and said brush can rest freely on said floor or carpet without any pressure being applied to said handle no matter whether the

5
10
15
20
25
30

floor is hard and supports said wheels without yielding or whether the carpet is thick and soft enough to let said wheels sink down in below the level of said brush, said means for dividing the weight of the sweeper including springs for transmitting a part of the weight to the wheels, and means for dividing any pressure applied to said sweeper by said handle between said wheels and said brush in another ratio, said weight dividing means and said pressure dividing means being proportioned so that the percentage of said handle pressure applied to said brush is greater than the percentage of said sweeper weight carried by said brush.
